UNITED STATES PATENT OFFICE.

CLEN S. HUMPHREY, OF BROOKLYN, NEW YORK.

DESIGN FOR A CONTAINER FOR TOILET POWDER OR OTHER COMMODITIES.

54,626.

Specification for Design.

Patented Mar. 9, 1920.

Application filed July 10, 1919. Serial No. 309,989. Term of patent 14 years.

To all whom it may concern:

Be it known that I, CLEN S. HUMPHREY, a citizen of the United States, and a resident of the city of New York, borough of Brooklyn, in the county of Kings and State of New York, have invented a new, original, and ornamental Design for a Container for Toilet Powder and other Commodities, of which the following is a specification, reference being had to the accompanying drawing, forming part thereof.

Fig. 2 is a plan view thereof.

The base of the design shown herein is oblong in form and the sides thereof taper inwardly to the top, which is circular in form.

I claim:

The ornamental design for a container for toilet powder and other commodities substantially as shown and described.

CLEN S. HUMPHREY.
